GAS DISPENSING DEVICE

Harold L. Norway, Evanston, Ill., assignor to The
Bastian-Blessing Co., a corporation of Illinois

Application May 27, 1941, Serial No. 395,443

21 Claims. (Cl. 62—1)

1

The present invention relates to liquefied petroleum gas equipment and more particularly to the method and apparatus for handling liquefied petroleum gas and is of special interest where a storage tank is buried below the frost line of the ground to absorb heat of the earth.

In many respects the embodiment employed to represent the present invention, is similar to that shown in my co-pending applications, Serial No. 375,079 filed January 18, 1941, and Serial No. 370,754 filed December 17, 1940, reference to which is hereby made, and to the extent that a similarity of parts exists between the embodiments of the several inventions, the disclosures of the above applications are incorporated herein for a better understanding of the present invention. These applications have matured into Patents Nos. 2,361,866 of October 31, 1944 and 2,400,570 of May 21, 1946.

The petroleum product employed in the system with which the present invention is concerned, is preferably a hydrocarbon fuel of the paraffin series such as butane or propane, or a mixture of both. Although the embodiment illustrated herein may operate under favorable conditions aboveground to dispense the fuel in the form of gas, the tank in which the fuel is stored is preferably located underground where the assistance of the heat of the earth is utilized with a reduction in pressure to vaporize the liquefied gas for use in a dwelling as a substitute for natural gas.

One of the ways of vaporizing the liquefied gas is the so-called "batch" system in which the vaporizer is carried on in the storage tank and vapor is withdrawn in the form of gas from the tank. The other way of vaporizing the liquefied gas is the so-called "flash" system in which the liquefied gas is withdrawn as a liquid from the tank and passed through a pressure reducing regulator which causes the liquid to flash into vapor.

Wherever vaporization takes place, heat units are absorbed from surrounding parts, and, in a batch system, this refrigerating action is expended largely throughout the tank, whereas with the flash system, the heat absorption is concentrated in a comparatively small space, namely around the pressure reducing device and adjacent parts.

Although many features of the present invention will improve vaporization and operating conditions for batch systems, the primary concern of the present invention is with flash systems, having for one of its objects the adaptation of the

2

flash process to take advantage of the benefits derived with batch systems, in that the refrigerating action is expended throughout the tank.

With the storage tanks buried below the frost line, the initial temperatures are sufficient to provide a substantial vapor pressure in the tank. This vapor pressure is constant at any given temperature and although it is relied upon solely in most installations to force liquefied gas or vapor from the storage tank, it cannot be relied upon or utilized for that purpose where the withdrawal of gas or the load upon the system is so great and continuous that the refrigerating action reduces the temperature of the tank contents below that necessary to keep the system going.

However, even in installations where this extreme condition takes place, there is available beyond the tank and around the service line sufficient ground heat below the frost line to maintain a supply of gas if the liquefied gas could be carried to it.

It is one of the purposes of the present invention to provide a safe and convenient means for assuring or continuing the operation of a system which has been subjected to the above mentioned extreme conditions, and as a corollary thereto, another object of the invention is to provide a means whereby air may be employed to force liquid from a tank when the liquid in the tank has been chilled to a temperature at which the vapor pressure of the liquid is insufficient to educt liquid from the tank and the heat available in the tank at that pressure is insufficient to accomplish vaporization of restricted quantities of liquefied gas.

Although air pressure has been used heretofore to handle gases of the class described, its use is impractical with batch vaporization because it is rapidly depleted as the vapor is withdrawn from the tank. On the other hand, with liquid eduction or flash systems the air remains in the tank but certain difficulties are incurred in handling it. The presence of air creates an increasing back pressure when the tank is being filled, and unless applied properly to a storage tank, the ultimate pressures which will exist in the tank are not immediately indicated.

An object of the invention is to provide an improved and safe system whereby air is utilized to augment eduction pressures.

A further object of the invention is to provide an improved means for applying the pressure to a container containing liquefied petroleum gas in which the sum of the partial pressures involved

is indicated immediately and to remove such pressure when upon occasion such becomes desirable as when the tank is being filled.

Another object of the invention is to provide a simplified and improved eduction arrangement for systems of the type described which is inexpensive to manufacture and maintain.

Another object of the invention is to provide an improved and simplified means for utilizing the sensible heat of the liquid in the tank to flash liquefied gas into vapor with an accompanying reduction of pressure.

A further object of the invention is to submerge in an anti-freeze solution, those parts of the system which are subjected to the refrigerating action that takes place during the vaporization which accompanies a reduction in pressure.

A further object of the invention is to reduce to a minimum the volume and the distance the liquefied gas has to travel beyond the tank to reach heat conducting parts which will assist in vaporizing any liquid in the eduction conduit.

A further object of the invention is to provide an improved means for preventing the filling of the tank above a predetermined level and further to provide a construction wherein the predetermined level at which such a means is operative in relation to the temperature of the liquid in the tank.

Another object of the invention is to utilize the equipment conventionally employed to fill, service and empty the tank. A further purpose of the invention is to provide a combination of tank and fitting constructions characterized by safeguards against unsafe removal of gas and other contingencies experienced in unloading pressure containers.

Another object of the invention is to provide a construction wherein the working parts of a vaporization regulator is disposed below the frost line, removed from contact with the earth and is disposed out of contact with any parts which are exposed to atmospheric temperatures.

These being among the objects of the present invention, other and further objects will be apparent from the drawings, the description relating thereto and the appended claims.

Referring now to the drawings:

Fig. 1 is a fragmentary vertical section taken longitudinally through the tank, standpipe and eduction means illustrating a preferred embodiment of the invention.

Fig. 2 is a plan view, on an enlarged scale, of the fitting mounted upon the standpipe shown in Fig. 1.

Fig. 3 is a side elevation of the construction shown in Fig. 2.

Fig. 4 is a section taken upon the lines 4-4 of Fig. 2.

Fig. 5 is a vertical section taken of the eduction means shown in Fig. 1.

Fig. 6 is a fragmentary view taken upon lines 6-6 in Fig. 2.

Fig. 7 is an enlarged section of a fitting by which air may be introduced or removed through the device illustrated in Fig. 6.

Referring now to the drawings in further detail, a pressure tested, corrosion treated tank 10, as shown in Fig. 1, is buried in the ground 11 below the frost line 12 thereof to absorb heat from the earth for the purpose of warming the liquid stored in the tank, the approximate maximum level of which is indicated by the broken line 13.

With this arrangement the heat of the proximate earth is utilized to establish vapor pressure

in the tank which operates to force fuel from the tank through an eduction conduit indicated generally by the numeral 14.

The tank is provided with a riser pipe 15 which is welded at the lower end thereof to the tank 10 as at 16 where it is disposed over an opening 17 in the top of the tank.

At its top, the pipe 15 receives thereon a concrete curb box having a cover 21 secured thereto by bolts 22, a bleeder opening 23 being provided to vent the box 18. The length of the pipe 15 is determined in relationship to the depth at which the tank 10 is expected to be buried. However, due to the box arrangement, a wide tolerance is provided for any particular tank and standpipe size because of the fact that the top of the pipe may be disposed at a point high or a point low in the box and thereby certain allowances be made for local conditions.

The upper end of the pipe 15 is threaded as at 24 to receive a companion flange member 25 for a body 26 bolted thereby by bolts 27 as sealed against pressure by a gasket 28 more particularly shown in tank 4. The body 26 comprises a forging capable of being made by two dies whose line of separation follows the outline contour of the body as seen in the sectional view in Fig. 4. The body 26 before machining comprises a central portion 30, upwardly extending bosses 31 and 32 thereon, and a preferably symmetrically contoured or hexagonal flange 33 around the bottom. Recesses 34 are provided beneath the boss 32 to afford room to receive the nuts 35 with a clearance adequate enough for ready assembly and removal.

In machining the body 26 the boss 32 is machined to receive the filler means preferably having a double valve construction. The boss 32 is drilled out and threaded to a depth as indicated at 36 at which point a shoulder 37 is provided beyond which the boss is hollowed out and internally undercut as at 38 to a depth 40 beyond which a restricted bore 41 is provided to receive the stem 42 of the valve 43. The valve 43 is held in place by a lock ring 45 threaded against the shoulder 37 and having a valve seat 46 machined on the inner face thereof to cooperate with the valve 43. A compression spring urges the valve 43 to seat against the seat 46. The lower end of the spring is received in a recess 47 in the body 30 to permit a greater flexing of the spring.

The valve 43 is hollowed out as at 48 to receive in supported relationship an upper valve 50 which carries a resilient seat 51 thereon. A retainer member 53 having a lip 52 machined upon the bottom thereof to form a valve seat is threaded into the bore as sealed with respect to the body by means of a gasket. A stem 54 upon the valve 50 reciprocably supports the valve in the bore 48 and the valve is urged into contact with the seat 52 by a spring 55.

The retainer member 53 at its upper end is internally threaded as at 56 and externally threaded with a coarse thread as at 57 to receive a bore connection (not shown). A closing plug 58 is received in the threads 56 and the plug is provided with a depending peripheral flange 60, which, when the plug is in place, overlies the threads 57 to protect them. A gasket 61 is mounted on a groove 62 in the housing section to provide a seal.

The valve areas are of different sizes but the valves operate preferably independently so that when a hose connection (not shown) is secured

to the housing by the threads 57 after the cap 58 is removed, the liquid inducted by the hose from a suitable source, under pressure of gravity or otherwise, comes against the valve 50 and opens it by compressing the spring 55 after which the pressure of the liquid is effective over a larger area to open the valve 43. Thereafter the liquid is free to flow into the tank through the bore 38 and the filler pipe 63 supported thereon which extends to a point proximate the bottom of the tank as indicated by the numeral 64.

At the lower end of the pipe 63 is threaded a fitting 65 containing therein a flap valve 66 which closes in the direction of incoming flow against the seat 67 when moved from its resting position by a rod 68 actuated by a float 70. The float is mounted upon an arm 71 pivoted as at 72 upon a collar 73 that is fastened to the pipe 63. A runner 74 engages an adjustable button 75 upon the end of the arm 68 to move the check 66 out into the stream of incoming liquid to be closed thereby when the float 70 reaches a predetermined level which is approximately that indicated by the line 43.

In view of the fact that the National Board of Fire Underwriters designate a fill limit in relationship to the temperature of the liquid, a means has been provided for varying the height at which the float 70 accomplishes actuation of the valve 65. The particular means shown is a bi-metal section 76 which flexes the float 70 upwardly with respect to the arm 71 in relation to an increase in heat and to move the float 70 downwardly with respect to the arm 71 when the temperature of the liquid in the tank is lower than that at which the arm 71 and section 76 would be in aligned positions.

The arm 71 is preferably pivoted at a point below the maximum expected fill level 43 so that the bi-metal section 76 is submerged as the level 43 of the liquid in the tank is approached. The bi-metal section 76 thereby is in direct contact and fully influenced by the sensible temperature of the liquid in the tank. Thereby, the float 70 is automatically adjusted to the temperature of the liquid so that it will operate to actuate the valve 65 by contacting the button 75 at the moment the maximum fill level for liquid at that temperature is reached. This is of especial interest where the sensible heat of the tank is utilized in the step of vaporization.

In this connection it might be well at this time to refer to the gauge construction since complex computations and graduations by the serviceman in determining the relationship between temperature and liquid level are eliminated, a direct reading of the level gauge being indicated in the weight of the liquid present in the tank, the criterion which is the ultimate basis involved in the sale of liquefied petroleum gas.

For purposes of mounting a liquid level gauge in the body 30, a bore, indicated at 78, is provided therethrough of proper dimension to receive a housing 85 of a liquid level gauge 80 and to accommodate the shaft 81 and provide room for visual examination of the interior of the tank when the gauge is removed, if upon occasion, such may be desired.

Around the upper part of the bore 78, a recess 82 is provided to receive the gasket 83 which is disposed below the flange 84 upon the gauge housing 85. The gasket 83 is compressed, to provide a seal, by means of four bolts 86 (Fig. 2) threaded into the metal of the body 30. The gauge is preferably a rotary acting magnetic

gauge with a dial 87 and hand 88 covered by a glass.

The gauge shaft 81 is operated by the float 70 by means of a thrust shaft 90, a weight 91 being provided to counterbalance the float 70 and provide a full normal operation thereof in relation to the true level of the liquid. The thrust arm 90 operates a rotably opposed lead nut 92 up and down along a helically threaded shaft 93 supported in a bracket 94 by means of collars 95 upon the pipe 63. The lead nut rotates the helical shaft progressively as it moves longitudinally, and the helical shaft in turn operates the float shaft 81. In this way movement of the float 70 about the pivot point 72 is translated to a rotary movement of the hand 88 in the gauge body 85 in relationship to the absolute volume of liquid present in the tank as related to its absolute weight.

20 In assembly, the float 70 and associated parts are inserted through the bore 78 if constructed as an assembly, and after mounting same with respect to the pipe 63, the entire assembly can be inserted into and removed from the tank through the riser pipe 15.

25 In this way a new and improved means is provided for preventing the overfilling of the tank that also obviates the necessity of providing a fixed level indicator so that warmer liquids may be filled to a higher level safely, thereby facilitating filling operations and the filling of the tank to its fullest level of safety irrespective of the temperature of the liquid introduced into the tank.

30 A pressure safety relief valve is installed in the boss 31 by drilling the boss out to the depth indicated at 100 beyond which a reduced bore 101 is provided around the mouth of which the valve seat lip 102 is machined to be engaged by a safety valve 103 held in place by a compression spring 104 backed up by an adjustable spider 105. The bore 101 is placed in open communication with the interior of the tank by means of a bore 106 so arranged that it can be made from the bottom of the body past the lip indicated at 107, a large bore 108 being provided in the bottom of the body to remove as much of the excess stock as possible from the bottom of the body 30.

35 In order to facilitate the filling of the tank a bleed relief is provided to remove any air and foreign vapor present in the top of the tank. This relief comprises an opening through the body 30 and in open communication with the tank as shown in phantom by the lines 111 in Fig. 3, wherein an adapter nipple 112A (Fig. 3) having mounted therein a Dill valve 113 such as shown in Fig. 6 serves as a check valve that can be opened by means of a hose connector 114 such as that shown in Fig. 7 where the body portion 115 is adapted to engage a top 116 of the Dill valve stem 117 whenever the plug 118 is removed by loosening the lock nut 121A. A similar lock nut 121A upon the hose connection, when tightened in place, forces the body portion 115 against the stem head 116. The hose (not shown) may or may not be present upon the nozzle 112 of the connector 114.

40 By way of informing the serviceman of an effective pressure present in the tank, a pressure gauge 119 is provided as threaded into the body 26 at 120.

45 One of the features of the present invention is the provision of a means whereby air pressure may be applied to the tank to boost the pressure therein so that after sustained heavy withdrawals of gas and when the sensible heat in the tank

50 is insufficient to vaporize the liquid, the air pres-

sure will force the liquid along the service line to a point where heat is available. This means is shown in Fig. 6 in which the threading upon the adapter nipple 112 is different from the threading on the nipple 112a and a small diameter tube 123 is secured to the bottom thereof to extend to a point adjacent the bottom of the tank as indicated by the numeral 124 in Fig. 1. The threading may differ in pitch or direction of helix, preferably the latter, in which case one of the threads upon the adapter nipple 112 is a right hand thread and that upon the adapter nipple 112A is a left hand thread. This prevents the use of air pressure equipment upon the wrong adapter nipple.

The adapter 121A is connected to a source of air under pressure and the air entering the tank is forced to bubble up through the liquefied petroleum gas in a manner by which diffusion is immediate and the added partial pressures are immediately indicated upon the gauge.

If air were to be introduced into the tank as an undiffused body, the partial pressure thereof would not be additive to the vapor pressure in the tank. If such occurred the serviceman would continue to force large volumes of air into the tank without additive pressures being registered until long after the serviceman had completed his call.

The air pressure added is preferably 20 to 25 pounds per square inch, which when applied with an approximately 10% outage will be effective to educt liquid when outage is above 80%.

The opposite threading of the two adapters also prevents the serviceman connecting the vent and bleed to the wrong opening and running the chance of removing liquid from the bottom of the tank instead of vapor and air from the top of the tank. Although an improved and safe means is provided for the handling of air pressure to assist vapor pressure in the tank, and although air pressure is preferred, other gases such as nitrogen may be employed upon occasion without departing from the teachings of the present invention provided such gases are those which are not absorbed to any material extent by the liquefied petroleum gas such as carbon dioxide would be.

A further and improved feature of the invention resides in the manner in which liquid is withdrawn from the tank for purposes of vaporization. In the embodiment illustrated, such comprises a conduit 130 threadedly carried by a collar 131 which is mounted upon the flange 132 welded to the tank 10 as at 133 over an opening 134 in the tank, which opening is large enough to receive the tube 130 therethrough after the tank has been assembled. The collar 131 is secured to the flange 132 by means of a coupling nut 135 which, when tightened, establishes a seal between the body 131 and the flange 132 by compressing a gasket 136 disposed therebetween. At the lower end of the conduit 130 a fitting 137 is internally threaded thereto as at 138, which fitting can be admitted into the tank through the opening 134, and has a downwardly presenting valve seat 140 therein surrounding a bore 141.

A cap 142 closes the bottom end of the fitting and has therethrough, inlet openings 143 by which liquefied gas in the tank can flow into the valve compartment 144 which is provided in the lower portion of the fitting 137. A valve 145 is disposed in the valve compartment and carries a valve disc 146 which cooperates with the valve seat 140. The lower end of the valve member is provided with a stud 147 which cooperates

with the guide bore 148 provided in the cap so that the valve 145 may reciprocate to carry the valve disc into and out of contact with the seat 140. The valve body 145 has a hexagonal outer contour as indicated by the broken lines 151 so that liquid entering the valve compartment from the opening 143 can flow past the valve 145 and through the bore 141 when the valve is open.

In order to operate the valve, two springs are employed which oppose each other, the lower one of which 152, is supported in a groove 153 in the cap between the valve 145 and the cap 142 to urge the valve towards the valve seat. The other spring 154 is disposed above the valve as received in a groove 155 in the fitting 137. The upper spring 154 is preferably the stronger of the two springs, the valve consequently would be urged normally to open position, the two springs operating to stabilize the action of the valve in a beneficial manner by preventing any pounding or chattering.

The valve is controlled by means of a shaft 156 threaded through the valve disc 146 into the valve body 145 as indicated at 157. A shoulder 158 is provided upon the shaft to hold the valve disc against the valve member 145 and thereby to prevent the disc from sticking or adhering to the valve seat 140. The shaft 156 extends up to and beyond the upper end of the conduit 130 where it is threaded as at 160 to receive a plurality of elements thereon which will now be described, in connection with the regulator body 161 threaded to the collar 131 as at 162. The valve body is provided with an upwardly presenting shoulder 163 supporting a diaphragm 164 which is held in place by a regulator bonnet 165 threaded tightly into place thereagainst in the regulator body as at 166. The control of the valve 145 is such that it can be used as a regulator valve for regulating the pressure existing inside the conduit 130 or as a manual shutoff valve operable from above ground by means of a shaft 167 having a hand wheel 168 thereon disposed in the curb box 18.

Below and extending up through the diaphragm 164, a yoke 171 is received upon the threaded end 160 of the shaft 156 and is held in sealed relationship to the diaphragm by means of a diaphragm plate 172 threaded on the yoke and supporting the lower end of the regulator spring 173. A bonnet cap 174 is threaded into the bonnet 165 to adjust the tension upon the spring 173 to regulate the pressure at which the diaphragm will operate to close the valve 145. In determining this adjustment of the cap 174, a sleeve 175 is externally threaded to the bonnet 165 as at 176 to provide a stop 177 to determine the maximum tension developed for the spring 173, the sleeve 175 being locked in place by a jam nut 178. A shaft 181 is threaded to the upper end of the shaft 156 and extends through an opening 182 in the top of the cap 174 beyond which the head 183 is provided to be engaged by the cap 174 when the cap 174 is turned not only to loosen the tension upon the spring 173, but also to close the valve 145.

The valve shaft 167 has a four prong construction 184 on the bottom thereof which engages corresponding recesses 185 upon the cap whereby the cap may be manually manipulated by means of the hand wheel 168 in the curb box 18.

In this construction, it is preferred that the threading 176 upon the sleeve 175 and the thread-

ing by which the cap 174 is mounted in the bonnet, be in opposite directions, one a left hand, and one a right hand thread, so that tightening and loosening the cap 174 by means of the wheel 168 will not operate to disturb the set of the predetermined relationship between the sleeve 175 and the lock nut 173. It is preferred that the threading of the cap 174 be the one which has the left hand relationship since it is natural to turn a wheel such as a hand wheel 168 clockwise to close the valve and counter clockwise to open it. Thus, when the hand wheel 168 is turned clockwise, the cap 174 runs outwardly to engage the head 183 to draw the valve 145 shut, and when turned counter clockwise as when opening the valve, the cap 174 runs down against the stop 177, thereby releasing the diaphragm 164 and the valve 145 to the action of the pressure present in the conduit 130.

The construction thus shown and described preferably constitutes a first stage pressure reduction upon the educted gas and is preferably set at approximately 3# output pressure. The regulator body 161 is laterally threaded as at 186 to receive the service line 187 which runs to the second stage pressure regulator 188 with or without a vaporizer between the two regulator housings, which vaporizer, not shown, may be an underground vaporizer or aboveground vaporizer preferably using a convectively circulated liquid in the form of an anti-freeze. The second stage regulator 188 reduces the gas pressure to a service pressure of 11" water column which gas is then delivered to an appliance (not shown) through a pipe 191.

A casing 192 is provided over the regulator body 161 as shown in Fig. 1 with an opening 193 through the top thereof through which the forked end 184 of the hand valve will be introduced with sufficient clearance to take care of normally expected manufacturing tolerances developing in relationship to the position of the casing 192 and the regulator body 161. Although the casing 192 may be secured to the riser pipe 15 for the purpose of structural rigidity, it is preferred that any connection provided therebetween be as little heat conductive as possible so that cold air chilling the head 26 and the top of the riser pipe 15 will not be materially effective upon the casing 192. In the particular embodiment shown, an insulating amount of dirt is shown between the riser pipe and the casing 192 whereby the temperature in the casing 192 will be substantially the temperature of the ground below the frost line 12.

Having thus described the invention, the assembly of the several associated parts is had as follows:

After the riser pipe 15 and flange 132 are welded to the tank around their respective openings 16 and 134, the companion flange 25 is tightened in place at the top of the riser pipe as sealed by litharge, suitable directions being given to leave the companion flange in any one of six positions in which the bolts are so arranged that when the body 26 having the fill pipe and float thereon is lowered in position, the shaft 71 of the float will be in longitudinal alignment with the tank 10, the opening 17 being so located longitudinally of the tank that adequate room for the action of the float 70 is provided at one end of the tank. Once the body 26 is in position, the conduit 130 may be lowered and the union nut 135 tightened in place with the casing 192 secured in position by flanges 194 at the bottom

thereof secured to the tank. The tank and assembly parts are then ready for shipment and after burial in the ground, the concrete box is lowered in place with the hand wheel and shaft 5. 167 disposed so that the earth can be filled in around the installation as shown in Fig. 1.

The vent valve 113 is then opened as has been described and the filler connection 32 is secured to a tank truck after which liquefied gas is introduced into the tank through the valves 50 and 43. Once liquefied gas reaches the interior of the tank vapor pressure becomes effective there and the liquefied gas vapor being heavier than air, the air is compressed and forced upwardly 15. out the vent with little, if any, diffusion. After the level of the liquid has risen high enough for the bi-metal 76 to be submerged, the float 70, when the predetermined level 13 is reached, moves the flap valve 66 out into the stream of the incoming liquid which causes it to close. Further 20. action of the pump at the service truck is then by-passed back into the tank and overfilling of the tank 10 is positively prevented. Thereafter, the vent valve 113 is closed and the plug 118 25. returned in position and the air plug 122 is removed. A suitable connection leading from the source of air under pressure is attached to the adapter nipple 112 and air is forced down the tube 123 and out of the mouth thereof below 30. the level of the liquid where the air bubbles up through the liquid and becomes immediately diffused with liquefied gas vapor, the sum of the partial pressures of which are immediately indicated upon the pressure gauge 119. It is preferred to apply enough air to bring the tank pressure to approximately 20 lbs. per square inch 35. higher than the vapor pressure so that there will be sufficient pressure in the tank above vapor pressure at all times to force liquid from the tank regardless of the depth of the liquid therein or the increasing space the air has to occupy 40. before the tank is emptied. Thus, under the most extreme conditions of load upon the system, the air will be effective to force liquid from the tank up the conduit 130 and into the service line 187 where the earth heat or a vaporizer providing a source of heat will cause vaporization to take place to maintain a constant flow of gas to the appliance.

After the tank has been placed in operation with a supply of liquefied gas therein, liquid will flow through the opening 143 in a stream past the normally opened valve 145 into the passage 141 and conduit 130 where a reduction in pressure takes place by gas being used in an appliance. Under this reduction of pressure, the liquid will progressively vaporize, drawing heat from the fitting 137 which is supplied with heat by the body liquid in the tank until the pressure in the conduit is returned to 3# at which time 55. this pressure effective over the area of the diaphragm 164 will close the valve 145 until such time as the pressure in the conduit 130 drops again below the pressure of 3# gauge. In this way regardless of the vapor pressure in the tank, liquid is forced therefrom and flashed into vapor by the simultaneous reduction of pressure and the supply of latent heat of vaporization from the sensible heat present in the tank, which heat 60. is replenished from the surrounding earth, up to the point that the earth and the sensible heat of the liquid is capable of delivering sufficient heat for vaporization. After this limit is reached further vaporization of the liquid admitted to 65. the conduit 130 is accomplished outside of the

tank as where heavy withdrawal conditions exist.

Having thus described an embodiment of the invention, it will be apparent to those skilled in the art that various modifications and changes and arrangement of parts may be made therein without departing from the spirit of the invention, the scope of which is commensurate with the appending claims.

What is claimed is:

1. An apparatus for supplying fuel of substantially uniform composition and at a low pressure from a mixture of liquid hydrocarbons, said apparatus comprising an underground tank buried below the frost line, conduit means extending from said tank to a place where the fuel is consumed, said conduit including a section having its inlet adjacent the bottom of said tank and arranged to be normally covered by the body of liquid fuel in the tank, a second section connected with the first and terminating near the place of fuel consumption, and control means including a pressure reducing valve at said inlet, and a pressure regulator in said second section.

2. In a liquefied gas dispensing system of the class described, a pressure storage tank buried underground in heat exchanging relation with the surrounding earth, an eduction conduit leading from the bottom of the tank and through the tank, a pressure reducing valve at the inlet of said conduit, a gas service pipe connected to the outlet of said conduit and a pressure regulator connected to the service pipe.

3. For use in a liquefied petroleum gas dispensing system having a storage tank and a riser pipe connected thereto, a unitary fitting including means for supporting the fitting upon the riser pipe in sealed communication with the interior of the tank, a machined boss upon the fitting having a filling valve therein and a conduit in communication with said boss, said conduit extending to a point adjacent to the bottom of the tank, a liquid level responsive device carried by the fitting in association with the filling means, means for withdrawing liquid from the tank through said conduit, and means controlled by said liquid level responsive device to prevent overfilling the tank including a valve opening in the direction of outward flow of gas through said conduit.

4. A process of handling liquefied butane and butane mixtures as a gas comprising storing a body of liquefied fuel of the class described under a pressure greater than the vapor pressure of the liquefied fuel at ground temperature, simultaneously reducing the pressure upon a restricted portion thereof within the confines of the body to a predetermined pressure substantially less than the vapor pressure thereof at ground temperatures and subjecting said portions to heat exchange relationship with the remaining contents of the tank and discharging the vapors thus formed.

5. A fuel supply apparatus comprising a tank adapted to contain a liquefied gas under pressure, means for establishing a pressure in the tank above the vapor pressure of the liquefied gas, means to restrict and vaporize a portion of liquid in the tank including a tube extending from a point adjacent the bottom of said tank to a point outside said tank and an expansion valve for expanding said liquid in said tube said expansion valve being disposed in that portion of said tube which is within said tank.

6. In a liquefied petroleum gas dispensing system having a storage tank, an opening in a wall

thereof, a unitary fitting, means for securing the fitting detachably in the opening, a liquid level responsive device carried by said fitting, said fitting having a machined boss thereon communicating with the tank, a filling valve assembly in said boss, and means including a conduit extending into the tank and a flow blocking element to obstruct the flow of gas into the tank when said device is moved to a predetermined liquid level in the tank, said device and said last mentioned means being insertable into said tank through said pipe.

5 7. In a liquefied petroleum gas dispensing system having a storage tank and a riser pipe secured thereto, a unitary fitting, means for securing the fitting detachably to the riser pipe, said fitting comprising a machined opening communicating with the tank, a filling valve assembly in said opening, and means including a conduit connected to the filling valve assembly and extending to a point proximate to the bottom of the tank to prevent overfilling of the tank.

15 8. In a liquefied petroleum gas dispensing system having a storage tank and a riser pipe secured thereto, a unitary fitting, means for securing the fitting detachably to the riser pipe, said fitting comprising a machined opening communicating with the tank, a filling valve assembly in the opening and means associated with the filler valve and carried as an assembly insertable through the riser pipe for preventing further flow of liquid into the tank when the level therein reaches a predetermined height.

20 9. In a liquefied petroleum gas dispensing system having a storage tank and a riser pipe secured thereto, a unitary fitting, means for securing the fitting to the pipe, said fitting comprising a forged body having a machined opening therein in communication with the tank interior, a filler valve assembly in the opening comprising two spaced valves closing with the outward flow of gas from the tank and a conduit extending to the bottom of the tank, a liquid level responsive device carried by said fitting and means associated with said conduit and controlled by said device for preventing overfilling of the tank above a predetermined level.

25 10. A system of the class described comprising an underground storage tank for storing a liquefied gas including butane, means for introducing air under pressure thereto below the level of liquid therein, means for educting gas therefrom including a conduit leading from a point proximate the bottom of the tank, means for reducing the pressure in said conduit to a pressure between the vapor pressure of the stored gas and a service pressure, and service conduit means including a pressure regulator connected to said conduit.

30 11. A system of the class described comprising a storage tank having an opening therein, a unitary fitting closing said opening, a fuel filler valve in said fitting and a filler conduit extending therefrom to a point adjacent the bottom of the tank for introducing liquid fuel into said tank, a check valve in said fitting and a second conduit extending to a point adjacent the bottom of the tank for introducing air into said tank, and eduction means for withdrawing fuel from the tank including a vaporizer for absorbing heat from the contents of the tank and vaporizing the fuel withdrawn.

35 12. In a system of the class described, the combination of a storage tank and a pressure regulator, said pressure regulator including an

elongated valve chamber extending into said tank to a point adjacent the bottom thereof.

13. In a system of the class described, the combination of a liquid eduction conduit, extending to a point adjacent the bottom of the tank, means for maintaining a pressure in said conduit below the pressure in the tank under normal conditions, and means for providing a pressure in said tank above the normal vapor pressure of the contents thereof.

14. A system of the class described comprising a storage tank having an opening therein, a unitary fitting closing said opening, a fuel filler valve in said fitting and a filler conduit extending therefrom to a point adjacent the bottom of the tank, a second conduit extending from said fitting to a point adjacent the bottom of the tank for introducing air into said tank, said second conduit having a check valve therein, eduction means arranged to absorb heat from the tank including a vaporizer disposed in said tank and a pressure reducing device for reducing the pressure in said eduction means ahead of said vaporizer, and heat insulating material separating said eduction means from the atmosphere.

15. In a system of the class described, the combination of a storage tank and a pressure reducer, said pressure reducer including an elongated valve chamber extending into said tank to a point adjacent the bottom thereof, a diaphragm exposed to the pressure existing in the valve chamber, a valve carried by the chamber, and means interconnecting the diaphragm and valve for controlling the operation of the valve by the diaphragm.

16. A system of the class described comprising an underground storage tank for storing a liquefied gas including butane therein in both its liquid and vapor phases, means for introducing air under pressure into the tank below the level of the liquid therein and in direct contact with the liquid, means for educting gas from the tank including a conduit leading from a point proximate the bottom of the tank, means for reducing the pressure in said conduit, and service conduit means leading from said pressure reducing means including an element for delivering the gas to a consuming device at service pressure.

17. In a liquefied petroleum gas dispensing system having a storage tank, a fitting adapted to be secured in sealed relation to the tank and having a boss thereon, means for filling the tank through the boss including a self closing back flow check valve in the fitting, a liquid level responsive device supported on the fitting and extending therefrom, and means including a conduit for interconnecting the check valve and the interior of the tank in normally open communication and a normally open inflow check valve controlled by said device for limiting the amount of liquid which may flow into the tank through said conduit.

18. A method of handling a liquefied gas comprising storing a body of gas underground in both its liquid and vapor phases in heat exchange relationship with the earth, progressively separating gas in its liquid phase from the remaining body within the confines of said body to provide a stream of gas segregated from the body

70

but in heat exchange relationship with the liquid remaining in the body, reducing the pressure on the separated gas to a substantially constant pressure as it is progressively separated, and simultaneously with said reduction of pressure supplying to the separated gas its latent heat of vaporization from the sensible heat of the remaining liquid to flash the separated gas into vapor, and after vaporization conducting said vapor to a place of use at a service pressure.

19. A method of handling a liquified gas comprising storing a body of gas in both its liquid and vapor phases, progressively separating gas in its liquid phase from the remaining body within the confines of said body, reducing the pressure on the separated gas to a substantially constant pressure simultaneously with said separation of the gas, and simultaneously with said separation and pressure reduction supplying latent heat of vaporization from the sensible heat of the liquid remaining in said body to the separated gas as it is being separated to flash the separated gas into vapor, and after vaporization conducting said vaporized gas to a place of use at a service pressure.

20. A process of dispensing vaporizable liquified gas as a vapor from a body of liquified gas stored under pressure in both its liquid and vapor phases comprising separating gas in its liquid phase from the remaining body of gas, simultaneously with separating the gas reducing the pressure thereon in heat exchange relationship with the remaining liquid present in said body, and through said heat exchange relationship supplying from the sensible heat present in said remaining liquid to said separated gas the latent heat of vaporization required to flash the separated gas into vapor, and thereafter further reducing the pressure on said vapor to a service pressure.

21. A process of discharging a vaporizable liquified gas as a vapor from a body of liquified gas stored in both its liquid and vapor phases comprising progressively educting liquid from said body to separate it therefrom at a point near the bottom of said body, reducing the pressure on said educted liquid to a predetermined substantially constant pressure as it is being separated, warming the educted liquid with the sensible heat present in the remaining liquid in said body to supply the latent heat of vaporization required to vaporize the educted liquid, and further reducing the pressure on the resulting vapor to a service pressure, said progressive eduction and said first reduction of pressure and said warming of the educted liquid taking place simultaneously and at substantially the same place.
